WOOD HEEL SLOTTING MACHINE

Albert C. Regge, Columbus, Ohio, assignor to
 Perma Corporation, Chicago, Ill., a corporation
 of Illinois

Application May 23, 1936, Serial No. 81,479

9 Claims. (Cl. 12—42)

This invention relates to an improved machine for slotting wood heels so that the latter will be adapted for the reception of mechanical fastening devices employed in uniting such heels in secured relationship with the heel seats of associated shoes.

In lieu of nailing wood heels to shoe bodies, it has been proposed to secure metallic attaching plates to the heel seats of shoe outsoles, and to provide these plates with spaced depending ears, which are receivable within slots provided in the bodies of such heels, transverse locking pins being provided which pass transversely through the heel bodies and the ears of the attaching plates positioned therein, whereby to provide a secure and effective fastening means for permanently and securely retaining wood heels in connection with their cooperative heel seats.

It is a primary object of the present invention to provide an improved machine for slotting wood heels in an accurate, economical and expeditious manner in order that such slots may receive and will be properly aligned with the securing ears of the metallic attaching plates.

A further object resides in the provision of gage means of an adjustable character by which heels of different size may be properly registered with the slot producing cutters of the machine so that slots of proper spacing and depth may be quickly and readily produced.

For a further understanding of the invention, reference is to be had to the following description and the accompanying drawing, wherein:

Fig. 1 is a top plan view of a wood heel slotting machine formed in accordance with the present invention;

Fig. 2 is a vertical transverse sectional view taken through the machine on the plane indicated by the line II—II of Fig. 1;

Fig. 3 is a vertical longitudinal sectional view taken through the machine on the plane disclosed by the line III—III of Fig. 2;

Fig. 4 is a perspective view of a wood shoe heel slotted in accordance with the present invention.

Fig. 5 is a perspective view of a slideable clamping plate used in connection with the machine.

Referring more particularly to the drawing, the numeral 1 designates a channel shaped supporting frame to the outer vertical surface of which is secured by means of bolts 2 a bearing block 3. This block carries a cross pin 4, the ends of which, as shown in Fig. 3, project beyond the vertical sides of the block. To these outwardly projecting ends are secured the upper ends 5 of coil springs 5, the latter having their lower ends

secured to pins 6 which are carried by a hollow heel receiving and supporting frame 7. One of the inner vertical walls 8 of said frame is formed with vertically extending dovetail guides 9 which are receivable within correspondingly formed slots or recesses 10 provided in the frame 1, the said guides providing for vertical movement of the heel receiving and supporting frame 7 with respect to the channel member 1 against the resistance exercised by the springs 5 when the frame 7 is advanced in a downward direction. When pressure is released, the springs serve to return the frame to its normal position.

Carried in connection with the channel member 1 is an electric motor 11, the armature shaft 12 of which extends, as shown in Fig. 3, through a slot 13 formed in one of the side walls of the frame or casing 7. The outer end of the shaft 12 removably carries for rotation therewith a pair of circular slotting cutters or saws 14 and the hub 15 of these cutters or saws rests for rotation in a trough 16 provided in the upper end of the bearing block 3. The latter is vertically slotted as at 17 to receive a spring pressed lubricating wick 18, normally in contact with the cutter hub 15.

The top wall 19 of the frame or casing 7 is formed with a rectangular opening 20, and at the forward end of this opening, the top 19 is equipped with a transversely extending gage bar 21. This bar is provided at its ends with slots 22 for the reception of screws 23 carrying wing nuts 24. The top 19 is provided with graduations for different heel sizes in order to effect accurate registration of the heels to be slotted with the cutters 14.

A wood heel 25, of the type disclosed in Fig. 3, is placed upside down on the top wall 19, with the breast edges or surfaces 26 of the heel in engagement with the gage bar 21. In addition, the heel is clamped in this position by the provision of a sliding plate 27 mounted for movement in a horizontal plane on the top 19 by having its ends arranged in parallel longitudinally extending guides 28. The plate 27 is provided with an angle member 29, which acts as a finger rest for the machine operator. Forwardly, the plate 27 includes a substantially V-shaped recess 30 of sufficient width to accommodate various sized heels. As shown in Fig. 5, the opposite edges of the recess 30 may be covered with an adhesive fabric so that when the plate is advanced into gripping engagement with an associated heel, it will not mar or injure the same.

In the operation of the machine, the gage bar 21 is first adjusted in relation to the graduations

24 in order to establish the proper relationship between the breast line 26 of the heel and the cutters 14, so that the vertical slots 31, produced in the upper surface of the heel, will be disposed in properly spaced relationship from the breast of the heel and, moreover, to insure the locating of the slots 31 so that they will properly receive the keeper ears of a metallic heel attaching plate provided on the sole of a shoe. Such a heel attaching plate has been disclosed in the patent to Eichhorn, No. 2,023,671, granted December 10, 1935. With the heel assuming the dotted line position disclosed in Fig. 3, the sliding plate 27 is advanced so that the V-shaped edges of the recesses 33 will grip the rounded back of the heel. The sliding of the plate is usually effected by the thumb of the operator's hand with the fingers resting on the top of the heel body. After the plate has been brought into clamping engagement with the heel, the operator applies downward pressure to the heel and to the top of the frame or casings 7. This causes the lowering of the frame and the heel mounted thereon so that the heel body will be brought into contact with the rapidly revolving cutters or saws 14, thereby producing the slots 31 within the heel. The depth of the slots is regulated by the engagement of the heel surface with the cutter hub 15. After the cut has been completed to the required depth, the operator merely releases pressure on the frame or casing 7 and the latter responds to the action of the springs 5 and returns to its normal position. The slitting operation may be quickly performed and slots produced in the heel bodies which will bear accurate relationship with the breast line of the heel. This accuracy in manufacture enables the heels to be readily assembled with shoe carried fastening devices to which the heels are ultimately attached.

40 What is claimed is:

1. A wood heel slotting machine comprising a frame, a drive shaft supported for rotation in connection with said frame and occupying an unchanging position with respect thereto, spaced cutters mounted for rotation in connection with said shaft, a heel supporting table, longitudinally extending guides formed with said frame on which said table is mounted for sliding movement at right angles to the axis of rotation of said cutters, spring means normally serving to maintain said table in spaced relation from said cutters, an adjustable gage bar carried by said table, and movable clamping means for maintaining the breast edge of a wood heel supported on said table in contact with said gage bar.

2. A machine for producing spaced slots in the seating surface of wood heels comprising a stationary frame, spaced cutters mounted for rotation on said frame, a heel support having an opening formed therein in registration with said cutters, means for removably clamping a wood heel on said support with the seating surface of the heel disposed in registration with said opening and said cutters, adjustable gage means for controlling the operative positions of a wood heel on said support in relation to said cutters, and means for resisting movement of said support toward said cutters.

70 3. A machine for producing spaced slots in the seating surface of wood heels for shoes comprising a stationary frame, a power driven shaft journaled in connection with said frame, spaced slot producing cutters mounted for rotation with said shaft in predetermined positions of opera-

tion, a heel support, vertical guides carried by said frame in which said support is confined for linear travel in a predetermined path, spring means cooperative with said support and resisting movement thereof from a normal position, and gage and clamping means carried by said support for maintaining a wood heel in a predetermined position thereon. 5

4. Apparatus for slotting wood heels for shoes comprising: a stationary frame, an electrical motor mounted on said frame, spaced circular cutters carried by the outer end of the shaft of said motor, a stationary bearing projecting from said frame and sustaining said shaft between said cutters, vertical guides carried by said frame, a heel support mounted for movement vertically within said guides and relative to said cutters, an adjustable gage bar carried by said support for contact with the breast edges of a wood heel occupying an inverted position on said support, and slideable clamping means carried by said support for confining a wood heel in a predetermined position on said support. 10 15 20

5. Apparatus for slotting wood heels for shoes comprising: a stationary frame, an electrical motor mounted on said frame, spaced circular cutters carried by the outer end of the shaft of said motor, a stationary bearing projecting from said frame and sustaining said shaft between said cutters, vertical guides carried by said frame, a heel support mounted for movement vertically within said guides and relative to said cutters, an adjustable gage bar carried by said support for contact with the breast edges of a wood heel occupying an inverted position on said support, and slideable clamping means carried by said support for confining a wood heel in a predetermined position on said support, and resilient means for resisting movement of said support from its normal position. 25 30 35

6. A machine for producing a transverse slot in the seating surface of wood heels for shoes comprising a stationary frame, a power driven shaft rotatably supported by said frame, a cutter secured to said shaft for rotation therewith, a heel support mounted on said frame for sliding movement in a direction angular to the axis of said shaft, a gage bar secured to said heel support, said gage bar being adjustable toward and away from the plane in which said cutter is arranged, and means carried by said heel support for clamping an inverted heel in position with the breast edges of the heel in engagement with said gage bar. 40 45 50

7. A machine for producing a transverse slot in the seating surface of wood heels comprising a stationary frame, a power driven shaft rotatably carried by said frame, a cutter secured to said shaft for rotation therewith, a heel support mounted on said frame and movable toward and away from said cutter in a direction perpendicular to the axis of said shaft, a gage bar secured to said support and extending transversely of said shaft, and heel clamping means mounted on said support for movement toward and away from said gage bar, said clamping means including a plate provided with a V-shaped notch having under-cut edges. 55 60 65

8. A machine for producing a transverse slot in the seating surface of wood heels comprising a stationary frame, a power driven shaft rotatably carried by said frame, a cutter secured to said shaft for rotation therewith, a heel support mounted on said frame for movement toward and away from said cutter in a direction perpen- 70 75

dicular to the axis of said shaft, a gage bar secured to said support, said bar being arranged at right angles to said shaft, heel clamping means mounted on said support for movement toward and away from said gage bar, said clamping means including a plate provided with a V-shaped notch having under-cut edges, and resilient gripping means secured to the edges of said notch.

5 10. A machine for producing spaced slots in the seating surface of wood heels for shoes comprising a stationary frame, a power driven shaft ro-

tatably carried by said frame, spaced cutters secured to said shaft for rotation therewith, a heel support carried by said frame for movement in a direction perpendicular to said shaft, a gage bar provided on said support, said gage bar being engaged by a heel positioned on said support, and a plate mounted on said support for movement toward and away from said gage bar, said plate being provided with a V-shaped notch to engage the back of said heel and properly locate the heel
